UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

THROW-OUT MECHANISM.

1,334,477.

Specification of Letters Patent. Patented Mar. 23, 1920.

Application filed May 21, 1917. Serial No. 169,903.

To all whom it may concern:

Be it known that I, ERASTUS E. WINKLEY, a citizen of the United States, residing at Lynn, in the county of Essex and State of Massachusetts, have invented certain new and useful Improvements in Throw - Out Mechanism; and I do hereby declare the following to be a full, clear, and exact description of the invention, such as will enable others skilled in the art to which it appertains to make and use the same.

This invention relates to throw-out mechanism for the purpose of rendering ineffective the operative instrumentalities of a machine, whenever necessary because of the absence of material to be operated upon or for any other reason.

One object of the invention is to produce throw-out mechanism applicable particularly to machines in which a crank-motion is employed to transmit power to the operative instrumentalities. To this end the invention comprises a novel construction by which the link which connects the crank with the parts actuated thereby may be rendered temporarily ineffective, so as to interrupt the transmission of power without arresting the motion of the crank.

Another object of the invention is to produce throw-out mechanism particularly suitable for use in a heel-compressing machine of the type illustrated in Letters Patent of the United States No. 776,875, granted December 6, 1904, to E. A. Tripp. In machines of this type the heel-compressing instrumentalities are actuated immediately by a toggle, which toggle is actuated, in turn, by power-mechanism including a fly-wheel. In accordance with the present invention the machine is thrown temporarily out of operation, without arresting the movement of the power-mechanism, by rendering ineffective the connecting-means by which power is transmitted from the power-mechanism to the toggle.

Other objects of the invention, and the features of construction and operation by which they are attained, will be set forth

hereinafter, in the description of the illustrated embodiment of the invention.

In the accompanying drawings illustrating the preferred form of the invention for carrying out the above objects, Figures 1 and 2 are, respectively, a side-elevation and a plan-view of a machine embodying the present invention; Fig. 3 is a plan-view of details of the automatic means for throwing the throw-out mechanism into operation; Fig. 4 is a side-elevation, partly in vertical section on line 4—4 in Fig. 2, showing particularly the connections between the crank-shaft and the toggle; Fig. 5 is a side-elevation of certain parts shown in Fig. 3; Fig. 6 is a side-elevation, in section on the line 6—6 in Fig. 2, of the parts shown in Fig. 4, in a different position of operation; and Figs. 7 and 8 are detail-views, in section on the lines 7—7 and 8—8, respectively, in Fig. 6, but on a larger scale than the latter figure.

The invention is illustrated as employed in connection with a heel-compressing machine of the type disclosed in the said patent to Tripp. This machine has the usual cross-head 10 (Fig. 2) which slides between vertical guides (not shown) formed in the uprights 12 of the frame of the machine. The cross-head is actuated by the usual toggle 14 (Fig. 1), driven by power-mechanism including a horizontal crank-shaft 16. This crank-shaft is geared to an intermediate shaft 17, which is also geared in the usual manner to a drive-shaft 19, and the drive-shaft is provided with the usual fly-wheel 21 for carrying the molding instrumentalities smoothly through that portion of their cycle of operations in which their movement is resisted by the pressure of the heel which is being compressed.

The drive-shaft 19 may be actuated in any suitable manner. Means for this purpose are shown as comprising a shaft 20, which is geared to the drive-shaft and is provided with a sprocket-wheel 22 by which it may be connected with any suitable source of power, through a sprocket-chain 24.

The crank-shaft 16 has the usual crank-

disks 26 (Fig. 2) which support, and are connected by, a crank-pin 28 (Figs. 4 and 6), and this crank-pin is connected, by a link or pitman 30, with the central pivot of the toggle, so as to buckle and straighten the toggle in the usual manner to lower and raise the cross-head.

A feature of the present invention resides in the peculiar construction of the pitman 30, this construction being such as to permit the pitman to be rendered, at will or through automatic means, ineffective to transmit power from the crank to the toggle, notwithstanding the continued rotation of the crank-shaft. The rear end of the pitman is greatly enlarged and has the form of a generally circular housing 32 (Fig. 6) which, for convenience in assembling the parts, is made in halves, as shown in Figs. 7 and 8, 20 these halves being secured together by screws 36. The two parts of the housing 32 are inwardly extended at the sides to form annular flanges 34 with an intermediate space of generally annular form.

25 The crank-pin 28 has a bearing in a disk 38 located in the circular opening within the side flanges 34 of the housing, and the disk is retained against lateral movement within the housing by two annular plates 40, which 30 are fixed to the sides of the housing by screws 42, the inner margins of these plates overhanging the margins of the disk (see Fig. 8).

35 The bearing for the crank-pin is located eccentrically in the disk 38, at a distance from the center of the disk equal to the length of the crank, that is to say, to the distance of the axis of the crank-pin from the axis of the crank-shaft (see Fig. 6). It 40 will be apparent, accordingly, that if the housing 32 be arrested in a position in which the axis of the disk coincides with the axis of the crank-shaft, while the disk is free to rotate in the housing, the crank-shaft may 45 then rotate freely, causing the disk to rotate in the housing but producing no movement of the housing or the pitman as a whole.

50 During the normal operation of the mechanism the effect just described is prevented by means which retain the disk 38 against rotation in the housing. The side-flanges 34 are provided, at one point, with radial slots 44 in which a transverse clutch-roller 46 (Figs. 6 and 7) is mounted, and 55 the disk is also provided, at its periphery, with a transverse recess 48 (Fig. 4) adapted to receive the clutch-roller. When the roller is retained in this recess it acts as a positive lock between the disk and the housing.

60 Two springs 50, fixed to the disk 38 and arranged in peripheral recesses therein (see Figs. 6 and 7) bear against the clutch-roller and tend to move it outwardly in the slots

44, so as to disengage it from the recess 48. 65 The movements of the clutch-roller are controlled, however, by a controller-ring 52 which is mounted loosely in the space between the side-flanges 34 of the housing and acts as a bearing for the disk 38. This ring 70 is provided with a recess 54 which has a cam-surface operable upon the clutch-roller. As shown in Fig. 6, while the left-hand end of the recess 54 is deep enough to permit disengagement of the roller from the recess 48, 75 the right-hand end is so shallow that when in engagement with the roller it locks it in the recess 48. Accordingly, by a slight partial rotation of the controller-ring 52 within the housing 32, the clutch-roller may be 80 either locked in operative position or released so as to be thrown outwardly by the springs 50.

The controller-ring is normally held in the position shown in Fig. 6, in which the 85 clutch-roller is held in operation. For this purpose the controller-ring is provided with a shoulder 56 which is free to move in an enlargement, or recess, 58 formed in the housing, and the projection 56 is connected 90 to one end of a tension-spring 60, which passes through an opening in the housing and is attached, at its other end, to the pitman. This spring tends constantly to draw the controller-ring to, and retain it in, the 95 position of Fig. 6.

The controller-ring is moved in the opposite direction by extraneous means. For this purpose it is provided with a second shoulder 62 (Fig. 6) movable in a second 100 recess 64 in the housing, and a pin 66, screwed into the shoulder 62, extends outwardly through an opening in the housing so as to project beyond the periphery thereof. This pin co-operates with a detent-member 68 which is in the form of a yoke, and 105 which is mounted to swing upon two coaxial pivot-studs 70. These studs are fixed in uprights 71 on the frame of the machine at opposite sides of the pitman and the 110 crank-disks (see Fig. 2).

The detent 68 is provided with a shoulder 72 which co-operates with the pin 66 when the detent is swung to the position shown in Fig. 4. Accordingly, if the crank-shaft 115 be rotated in a contra-clockwise direction the pin 66 will encounter the shoulder 72 and be arrested thereby, with the result that the normal movement of the controller-ring in unison with the housing is prevented. 120 This causes a relative movement of the controller-ring in the housing in a direction to release the clutch-roller 46, which is thereupon thrown out of operation by the springs 50, and the disk 38 is then free to turn with- 125 in the housing. The pin 66 and the detent are so located that the action just described takes place at the moment when the axis of

the disk 38 coincides with the axis of the crank-shaft, as shown in Fig. 4, which occurs at a time when the toggle 14 has been buckled sufficiently to lower the cross-head 5 and thereby move the heel-compressing dies out of co-operative relation to each other.

In order to arrest the movement of the pitman positively at the same moment that the clutch-roller 46 is released, the detent 10 is provided with a lug 74 arranged to co-operate with a shoulder 76 suitably located upon the periphery of the housing, as shown in Fig. 4. The parts when arrested, as just described, are in position to permit continued rotation of the crank-shaft and free rotation of the disk 38, while no movement is imparted to the pitman, and consequently the compressing dies remain inoperative.

It will be apparent that the throw-out mechanism just described is applicable to various machines operated by crank-mechanism, and that the detent may be thrown into and out of operation in various manners. Where this mechanism is employed, 25 as in the present instance, in a heel-compressing machine, it is proposed to control the detent automatically, by means associated with mechanism for feeding a succession of heels to the machine, these means 30 operating automatically upon any interruption in the supply of heels so fed. In this aspect of the invention the present construction is to some extent similar to that disclosed in a co-pending application Serial 35 No. 185,500 filed August 10, 1917, by the same applicant, in which application the general arrangement for interrupting automatically the operation of the heel-compressor is more particularly claimed.

The illustrated heel-compressor is shown as provided with automatic means for feeding to it a succession of heels, these means being the same as those disclosed in Letters Patent of the United States No. 1,213,052 granted to the present applicant January 45 16, 1917. The heels are brought to the machine on an endless chain-conveyer 78 (Fig. 1), of which each link in the upper stretch supports a heel 80 in inverted position. The 50 chain is supported by sprocket-wheels 82, mounted on a shaft 84 which has bearings on the fixed frame of the machine. Each heel, in turn, is removed from the chain by automatic transferring mechanism 86, which 55 operates in timed relation with the operation of the heel-compressor and places the heel upon the feed-slide 88 (Fig. 2) of the latter by which it is delivered, in the usual way, to the compressing dies. As the transferring-mechanism constitutes no part of the present invention, and is fully disclosed in the said Patent No. 1,213,052, it need not be described herein. As stated in said patent it is to be understood that the conveyer

78 is actuated in timed relation to the cycle 65 of operations of the heel-compressor, so as normally to supply heels at a rate suitable to the speed of operation of such machine.

In the present machine the throw-out mechanism is controlled by automatic means 70 which detect any hiatus or interruption in the supply of the heels upon the conveyer-chain. For this purpose two feelers 90 (Fig. 2) are employed, in the form of arms fixed to the upper ends of two parallel rock-shafts 75 92 and 94 which turn in bearings on the frame of the machine. These feelers are arranged to be engaged by each heel upon the conveyer, and thus swung apart as the heel passes the point of operation of the feelers. 80 The shafts 92 and 94 are thereby rocked, and as they are connected together by segmental gears 96, the feelers move always through equal distances in opposite directions, so that they do not displace the heels laterally upon 85 the conveyer, but act rather to center them correctly thereon. An arm 98, projecting from the shaft 94, is connected with a spring 100 which acts to swing the feelers toward each other after the passage of each heel. 90

Directly below the shaft 84 a shaft 102 is journaled, and it is connected with the shaft 84 by sprocket-wheels and a chain 104, so as to be rotated in unison therewith. The shaft 102 actuates the mechanism by which the detent 68 is controlled, and by which the time of operation of the detent is directly correlated with the passage of the heels through the compressor. This mechanism comprises a disk 106 (Figs. 1, 3 and 5), fixed on the shaft 102 and provided with a series of pins 108 which slide longitudinally in sleeves integral with the disk. Spring-pressed plungers 110, mounted to slide in the disk, bear frictionally against the sides of the respective pins, so that they tend to remain in any position into which they have been moved within the sleeves. 105

The pins 108 are employed as indicators to register the presence or absence of a heel 110 upon each link of the conveyer-chain, the rate of progression of the indicator-pins past any given point, as the disk rotates, being the same as the rate of progression of the chain-links 78, so that during the effective part of 115 its path of movement each indicator pin is representative of a heel passing through the machine from the point of operation of the feelers 90 to the compressing dies.

In order that the indicator-pins may be 120 set through the action of the feelers 90, an arm 112 is mounted upon a stationary pivot 114 adjacent the disk 106, and this arm has a beveled surface (Fig. 3) which, when the arm is in the position of Figs. 3 and 5, engages the end of each pin as it passes by and presses it outwardly (i. e. toward the observer as shown in Figs. 1 and 5.) The arm 125

- 112 is brought to the position shown whenever the feelers are spread apart by a heel, owing to the fact that the arm 112 is connected to the rock-shaft 94 through a rod 118. One end of this rod is pivoted to the arm while the other end slides through an opening in an arm 116 (Fig. 3) fixed to the rock-shaft. A collar 119, engages the arm 116 on one side, while a spring 120 bears against the other side of the arm and against a nut 122 on the end of the rod. By this arrangement the arm 112 is moved positively to the operative position of Figs. 1 and 5 at the passage of each heel on the conveyer.
- 15 The indicator pins coöperate with an arm 124 which is fixed on a short horizontal rock-shaft 126 journaled alongside the disk 106. This arm has, at its inner surface, a channel 128 which is normally traversed by the ends 20 of the indicator-pins when in the position to which they are brought by engagement with the wedge arm 112. The channel is of such length that as one pin leaves it another is about to enter it, so that so long as a constant succession of heels is supplied to the conveyer, and the indicator pins are set accordingly, the arm 124 is held immovable in the position shown in Fig. 5. A second arm 132 is fixed to the rock-shaft 126, however, and a spring 134 (Fig. 1), attached to this arm, tends to raise it and thereby swing the arm 124 to the right. Accordingly, if a heel is missing from the succession upon the conveyer-chain, and one of the indicator-pins 25 thus fails to be pushed outward by the arm 112, the arm 124 is released upon the emergence of the last preceding pin from the channel 128, whereupon it is swung to the right, as shown in Fig. 1.
- 30 The movement, just described, of the arm 124 causes the throw-out mechanism to become operative. The arm 132 is pivoted to the lower end of a link 136, of which the upper end is pivoted to an arm 138 (Fig. 1). This latter arm is fixed on the end of a transverse rock-shaft 140 journaled in bearings on the frame of the machine, and this rock-shaft carries two rearwardly projecting arms 142 (Fig. 2) each of which is connected to the upper link 144 of one of a pair of similar toggles, arranged at opposite sides of the machine. The lower link 146 of each toggle is pivoted to a stud 148 (Figs. 4 and 6) on one of the uprights 71. The middle 35 pivot 150 of each toggle is connected to one of the two parallel links 152 which are connected, at their rear ends, to the detent 68 by means of a pivot rod 154 journaled transversely in the detent.
- 40 As shown in Fig. 6 the toggles 144—146 are in a position such that the detent is swung back to inoperative position, but when the arm 124 swings to the right, as before described, the rising movement of the arm 132,

under the influence of the spring 134, is 65 transmitted through the link 136, and the connection just described, to the arms 142, which are lowered to the position shown in Fig. 4, thereby causing the lower link 146 of each of the two toggles to have a crank-like action upon the corresponding link 152 70 and thus draw the detent forwardly into operative position. Accordingly, the effective operation of the heel-compressor is interrupted or modified, and the various parts 75 of the mechanism are so arranged that this interruption occurs at the time when the cross-head has descended after the completion of the compressing operation upon the last heel withdrawn from the conveyer, by 80 the transferring mechanism 86, immediately preceding the hiatus in the succession of heels upon the conveyer.

The interruption of the operation of the compressor is not permanent, but is timed to 85 continue only for a number of cycles corresponding to the number of heels absent from the conveyer. In case only one heel is absent from the conveyer, for example, the arm 124, after having swung to the right 90 in consequence of the failure of the arm 112 to set one of the indicator-pins in its outward position, will presently be swung back again by the engagement, with its projecting extremity 156 (Fig. 5), of the next indicator-pin in succession, since this pin will have been set outwardly by the wedge arm 112, and in such a case the detent 68 will be thrown to inoperative position after it has arrested the operation of the machine for 95 one cycle only. If the hiatus in the succession of heels embraces more than one heel the number of cycles during which the machine is rendered inoperative will be equal to the number of heels missing, as it will 100 continue so long only as the indicator-pins are not set outwardly in the normal manner.

Each indicator-pin, after it has performed its function, is restored to its original inwardly projecting position by engagement 110 with the inner surface of the arm 124, this surface being inclined in the proper direction to slide the pin back to the inner side of the disk 106 as shown in Fig. 3.

An important advantage of the present 115 throw-out mechanism resides in the fact that it does not require a stoppage of the machine as a whole, but merely a modification of its operation which permits the power-mechanism, and particularly the heavy fly-wheel 21, to continue in normal operation. Furthermore, it acts to connect the crank with, and disconnect it from, the toggle 14 by which the cross-head is actuated, at a time when this toggle and the 120 parts actuated thereby are not in rapid motion, but are near the end of their cycle of operations, so that the movement of these

parts may be stopped and resumed with no substantial shock. It is these features of the throw-out mechanism which render it particularly applicable to a heel-compressor, 5 and permit the compressor to be stopped and started as promptly as is necessary to interrupt its effective operation only for the exact number of cycles corresponding to the number of heels which may be missing from 10 the conveyer. If it were necessary to stop the entire machine in such a case it would be impossible to resume its operation immediately upon the resumption in the succession of heels, owing to the inertia of the 15 parts which would have to be started.

The invention is not limited to the embodiment thereof hereinbefore described and illustrated in the accompanying drawings, but it may be embodied in various other 20 forms within the scope of the following claims.

What is claimed as new is:—

1. A heel-compressor having, in combination, compressing members, a continuously 25 operating power-mechanism, a normally operative driving connection between said members and said power-mechanism for continuously actuating said members through periodic cycles of operation, and automatic 30 means for interrupting said driving connection when the compressing members occupy their open positions and during the continued operation of said power-mechanism.

2. A heel-compressor having, in combination, compressing members, a toggle for actuating said members, a continuously operating crank-shaft, a normally operative driving connection between said toggle and said crank-shaft for continuously operating said 40 toggle and said compressing members through periodic cycles of operation, and automatic means for rendering said driving connection inoperative to arrest the operation of said toggle and compressing members 45 during the continued operation of said crank-shaft.

3. Throw-out mechanism having, in combination, a continuously rotating crank, a driven member, a two part driving connection between the crank and the driven member, and means for normally preventing relative movement of said parts to cause them to act as one to continuously actuate said driven member through periodic cycles of 50 operation, said means being movable, during the continued rotation of the crank, to an inoperative position in which said parts are permitted a relative movement whereby said connection is rendered ineffective to transmit power from the crank to the driven member.

4. Throw-out mechanism having, in combination, a crank; a driven member; a pitman connected to the driven member; a con-

necting-member rotatably mounted in the 65 pitman and having a bearing, in which said crank turns, located at a distance, from the axis of rotation of the connecting-member, equal to the length of the crank; means for normally retaining the connecting-member 70 against rotation relative to the pitman; and means for throwing said retaining means out of operation and for arresting movement of the pitman in a position in which the axes of rotation of the connecting-member and 75 the crank coincide.

5. In a heel-compressor comprising dies of which one is movable toward and from the other to compress and release a heel between the dies, and power-mechanism, including a fly-wheel, for actuating the movable die; normally operative power-transmitting connections between the power-mechanism and the movable die to continuously reciprocate said die, and throw-out 85 mechanism operable on said connections to modify their action so as to prevent movement of the movable die to heel-compressing position during continued operation of the power-mechanism. 90

6. A heel-compressor having, in combination, relatively movable compressing members, a continuously operating power mechanism, means including a normally rigid two-part driving pitman connected between said 95 power mechanism and one of said compressing members for continuously reciprocating said compressing member, and means for disconnecting the component parts of said driving pitman to interrupt the operation 100 of the movable compressing member during the continued operation of said power mechanism.

7. A heel-compressor having, in combination, relatively movable compressing members, a toggle for actuating one of said members, a continuously operating crank-shaft, normally operative disengageable driving means for connecting said crank-shaft to said actuating toggle and continuously operating the movable compressing member through periodic cycles, and means to disengage said last means when said compressing members are in open position. 105

8. Throw-out mechanism having, in combination, a continuously rotating crank, a driven member, and means for transmitting power between said crank and said driven member comprising a pitman having a circular recess in the crank end thereof, a rotatable disk disposed therein and eccentrically connected to said crank, means for normally connecting said disk and said pitman whereby by said driven member is continuously operated through periodic cycles, and means 115 for rendering said connecting means inoperative to arrest the operation of said driven member. 120

125

9. A heel-compressor having, in combination, compressing members, a continuously operating power-mechanism, a normally operative driving connection between said member and said power-mechanism for continuously actuating said members through periodic cycles of operation, and means for interrupting said driving connection during the continued operation of said power-mechanism, whereby said compressing members are rendered inoperative.
10. A heel-compressor having, in combi-

nation, compressing members, means for supplying heels to said compressing members, a continuously operating power-mechanism, a normally operative driving connection between said members and said power-mechanism for continuously actuating said members through periodic cycles of operation, and automatic means responsive to a failure of the supply of heels for interrupting said driving connection during the continued operation of said power-mechanism.

ERASTUS E. WINKLEY.
